Primary Examiner — W. A. Teddy Falloway

Assistant Examiner — Sarah J Ault

(57) **CLAIM**

The ornamental design for a modular pendant, as shown and described.

DESCRIPTION

FIG. 1 is a front perspective view of a modular pendant shown configured in a first configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the modular pendant of FIG. 1 shown configured in a second configuration;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front perspective view of the modular pendant of FIG. 1 shown configured in a third configuration;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The broken lines showing a clasp feature illustrate portions of the modular pendant and the broken lines showing a chain depict environmental structure. The broken lines form no part of the claimed design.

1 Claim, 21 Drawing Sheets
